US0D1077577S

(12) **United States Design Patent** (10) **Patent No.:** **US D1,077,577 S**
(45) **Date of Patent:** **** Jun. 3, 2025**

(54) **WATER CUP**

(71) Applicant: **Foshan Shunde Woheyng Electric Co., Ltd.**, Foshan (CN)

(72) Inventor: **Xiaogang Wu**, Foshan (CN)

(73) Assignee: **Foshan Shunde Woheyng Electric Co., Ltd.**, Foshan (CN)

(**) Term: **15 Years**

(21) Appl. No.: **29/980,764**

(22) Filed: **Dec. 26, 2024**

(51) **LOC (15) Cl.** 07-01

(52) **U.S. Cl.**

USPC **D7/507**; D7/510; D7/624.2

(58) **Field of Classification Search**

(57) **CLAIM**

The ornamental design for a water cup, as shown and described.

DESCRIPTION

FIG. 1 is a front perspective view of a water cup, showing my new design;

FIG. 2 is a rear perspective view thereof, shown with compartment cover closed for clarity of disclosure;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of my new design, shown with compartment cover open and sliding door closed for clarity of disclosure;

FIG. 10 is another perspective view thereof, shown with sliding door partially open for clarity of disclosure; and, FIG. 11 is another perspective view thereof, shown with sliding door fully open for clarity of disclosure.

The broken lines in the drawings illustrate the portions of the water cup, which form no part of the claimed design.

1 Claim, 11 Drawing Sheets
